WATERSLED

Russell G. Heston, Jr., Little Silver, N.J., and Wesley F. Junker, Copiague, N.Y., assignors, by mesne assignments, to Union Carbide Corporation, New York, N.Y., a corporation of New York

Filed Aug. 2, 1966, Ser. No. 3,316

Term of patent 14 years

(Cl. D71—1)

FIG. 1

FIG. 2

FIG. 3

FIG. 1 is a perspective view, taken from the front and above, of a watersled showing my new design, the side not shown being identical in appearance as the side shown therein;

FIG. 2 is a plan view showing the bottom of the watersled; and

FIG. 3 is an elevational view showing the rear thereof.

We claim:

The ornamental design for a watersled, substantially as shown and described.
